Primary Examiner — T. Chase Nelson*Assistant Examiner* — Mark Cavanna(74) *Attorney, Agent, or Firm* — Choate, Hall & Stewart LLP; Charles E. Lyon(57) **CLAIM**

The ornamental design for a radiation probe, as shown and described.

DESCRIPTION

FIG. 1 is a perspective view of a radiation probe showing our new design;

FIG. 2 is a top view thereof;

FIG. 3 is a front view thereof;

FIG. 4 is a bottom view thereof;

FIG. 5 is a rear view thereof;

FIG. 6 is a left side view thereof; and,

FIG. 7 is a right side view thereof.

The broken lines depict portions of the radiation probe that form no part of the claimed design.
